UNITED STATES PATENT OFFICE.

AUBREY C. HARRY, OF PORTSMOUTH, OHIO.

PORTABLE WALL-PAPER HANGER.

1,075,824.

Specification of Letters Patent.

Patented Oct. 14, 1913.

Application filed February 14, 1913. Serial No. 748,447.

To all whom it may concern:

Be it known that I, AUBREY C. HARRY, a citizen of the United States, residing at Portsmouth, in the county of Scioto and State of Ohio, have invented new and useful Improvements in Portable Wall-Paper Hangers, of which the following is a specification.

The invention relates to wall papering machines and more particularly to the class of portable paper hanging machines.

The primary object of the invention is the provision of a machine of this character wherein the ceiling and walls of a room can be readily and easily papered without requiring the hand application thereof.

Another object of the invention is the provision of a machine of this character wherein the paper strips will be cut into the required lengths after the same have been applied to the ceiling or walls of a room.

A further object of the invention is the provision of a paper hanging machine wherein the paste roller is fed with paste in a novel manner so as to assure the required coating of one face of the wall paper strip prior to the hanging of the same to a wall or ceiling.

A still further object of the invention is the provision of a paper hanging machine wherein the paper will be applied to a wall or ceiling in a smooth and even manner, and also which will enable the proper matching of the strips when being applied thereto.

A still further object of the invention is the provision of a machine of this character which is extremely simple in construction, thoroughly reliable and efficient in its operation, strong, light in weight, and also which may be manufactured at a minimum expense.

With these and other objects in view the invention consists in the construction, combination and arrangement of parts as will be hereinafter fully described, illustrated in the accompanying drawing, and pointed out in the claims hereunto appended.

In the drawings:—Figure 1 is a fragmentary side elevation of a wall showing in top plan the machine constructed in accordance with the invention and in position for applying the paper to the wall. Fig. 2 is a side elevation of the machine. Fig. 3 is a vertical longitudinal sectional view thereof. Fig. 4 is a front elevation. Fig. 5 is a rear elevation.

Fig. 6 is a fragmentary side elevation showing the cutter in position for severing the wall paper strip. Fig. 7 is a sectional view on the line 7—7 of Fig. 2. Fig. 8 is a plan view of the paste tank and the paste applying roller mounted thereon. Fig. 9 is a bottom plan view of the machine. Fig. 10 is a fragmentary vertical longitudinal sectional view through the frame showing in detail one of the sockets for receiving one limb of the operating handle.

Similar reference characters indicate corresponding parts throughout the several views in the drawing.

Referring to the drawings by numerals, the machine comprises a frame including upwardly arched side sections 10 and an upper or top cross connecting bar or brace 11, the side sections being formed in their upper edges with sockets 12 in which are received the ends of the limbs 13 of a forked handle 14, the latter being designed for the convenient manipulation of the frame to move the same over a ceiling or wall. Arranged between the side sections 10 of the frame at the forward or front end thereof is a presser and smoothing roller 15, the journal ends 16 each engaged in a bearing 17 slidably mounted in a guideway 18 formed in the inner side of each side section 10. Arranged within each guideway 18 is a coiled compression spring 19 which acts upon the bearing 17 so as to hold the roller 15 normally projected beyond the lower edge of the side sections 10 of the frame, yet the said roller 17 is free to be retracted from the said position under the tension of the springs 19 to act upon the wall paper for smoothing and applying the same to a ceiling or walls in a manner hereinafter described.

Passed through the side sections 10 for intersecting the sockets 12 to engage the ends of the limbs 13 of the handle 14 is a removable pin 20 which detachably fastens the handle to the frame, the handle being removed when the machine is to be carried from one locality to another, and in this manner assures the convenient handling of the machine.

Mounted in the frame and suitably secured to the side sections 10 thereof is a paste reservoir or tank 21 provided with a loop shaped feed tube 22, the same being extended rearwardly of the tank and has formed in its medial portion 23 a delivery

slot 24 in which is arranged a paste applying roll 25, the journal ends 26 of which being journaled in the side stretches or portions of the feed pipe 22, and this roller 25 receives paste from the feed pipe 22 and applies it to the wall paper when fed through the machine in a manner presently described.

5 Journaled rearwardly of the feed pipe 22 and spaced therefrom is a wall paper supporting or delivery roll 27, the same being 10 detachably journaled in the side sections 10 of the frame and is provided with a slot 28 in which is engaged one end of the wall paper strip 29 which is normally wound 15 thereon and is adapted to be fed through the machine when applying the same to a ceiling or wall.

Suitably journaled in the lower edges of the side sections 10 of the frame near the 20 rear end thereof are friction rollers 30 which are adapted to travel upon the wall or ceiling when the wall paper is being applied thereto so as to assure the easy travel of the machine and to prevent the frame 25 from contacting therewith during the working of the machine.

The lower edges of the side sections 10 of the frame at the forward portion thereof are provided with grooves or channels 31 30 to accommodate arms 32 which are pivoted at 33 in the said grooves or channels for rocking movement, the forward ends of the arms being loosely connected to the journals 16 of the roller 15, while the rear ends of 35 the arms are connected with a combined guide and controlling roll 34, the latter having its ends extended into guideways 35 formed in the inner faces of the side sections 10 and over this roller is adapted to be 40 trained the wall paper 29 when fed to the presser roll 15, the roller 34 being designed to coöperate with a cross piece 36 which is arranged at the inner side of the latter so that when the pressure is relieved from 45 the presser roller 15 the roller 34 will be automatically moved toward the piece 36 for gripping the paper to hold the same from being further unwound from the delivery roll 27, but when pressure is applied 50 to the presser roll 15 for the application of the wall paper 29 to the ceiling or wall, the roll 34 is moved away from the cross piece 26, thereby permitting the wall paper 29 to be freely unwound from the delivery roll 27 55 so that it can be applied to the ceiling or wall during the travel of the machine there-over.

The wall paper 29 prior to the training of the same over the roller 34 is passed over 60 the medial portion 23 of the feed pipe 22 so as to lie between the paste applying roll 25 and a curved guide plate 37 which is suitably fixed in the frame contiguous to the medial portion 23 of the feed pipe 22 65 so as to extend partially about the said me-

dial portion 23 and thereby sustain the paper 29 in contact with the paste roll 25 so that paste will be applied therefrom to one side of the paper while passing over the same. The plate 37 has journaled thereon a guide roller 38 which is located at one edge thereof so as to prevent the tearing of the paper when being fed to the presser roller 15 during the operation of the machine.

70 Loosely connected to the journals 16 of the presser roll 15 are the side limbs 39 of a cutting knife 40 which is provided with a toothed cutting edge 41, and this knife 40 is adapted to be swung toward and away from the paper 29, and when moved into contact with the said paper will sever the same. At 75 a point between the tank 21 and the knife 40, and journaled in the frame, is a crank shaft 42 to the cranks 43 of which are 80 loosely connected links 44, the same being also loosely connected to the knife 40, while connected to the remaining crank 45 of the said shaft 40 is an operating rod 46 which extends to the handle 14 and is connected 85 to an operating lever 47 pivoted at 48 to the handle 14, the lever 47 when actuated being 90 designed to shift the knife 40 into cutting relation with respect to the paper 29 for severing the same. Fixed on the operating 95 rod 46 is an abutment 49, while fixed in one side section 10 of the frame is a guide eye 50 through which is passed the rod 46, and surrounding the latter is a coiled expansion 100 spring 51, the ends of which work against the abutment 49 and the eye 50, and this spring is designed to normally hold the knife 40 away from the wall paper 29 so as to prevent the accidental cutting thereof. On operating the lever 47 the knife can be 105 moved into contact with the wall paper 29 for severing the same into the required length.

In the operation of the machine for applying wall paper to the ceiling or walls of 110 a room, the wall paper is wound upon the delivery roller 27 and initially the said paper is trained over the medial portion 23 of the feed pipe 22, thence between the guide roll 34 and the piece 36 and finally 115 beneath the presser roller 15. The initial feed of the paper in this manner is accomplished by hand. Now, upon shifting the machine over the ceiling or wall the paper 29 is applied thereto, it being understood 120 that the paper when being fed from the machine is supplied with paste on one side thereof from the paste roll 25. When pressure is applied to the machine the presser roller 15 will act upon the paper 29 so 125 as to lay the same smooth upon the wall and cause it to adhere thereto. The pressure upon the machine causes the said roller 15 to retract against the tension of the springs 130 and in this manner the roll 34 is auto-

matically shifted from the piece 36, thus freeing the paper 29 so that it will freely unroll from the delivery roll 27 during the travel of the machine over the ceiling or wall for the application of the paper thereto.

5 The operator of the machine can readily inspect the wall paper 29 through the body of the machine so as to ascertain whether the strips of paper are being properly matched when papering a ceiling or the 10 walls of a room.

From the foregoing it is thought that the construction and manner of operation of the device will be clearly understood, and therefore a more extended explanation has been 15 omitted.

What is claimed is:—

1. A machine of the class described, comprising a frame, a presser roller journaled in 20 the forward end of the frame, and held displaceable, a paper supporting roll adapted to feed paper to the presser roller, a paste tank fixed in the frame and adapted to supply paste to one side of the paper, and means 25 normally engaging the paper to hold the same against feeding movement and automatically shifted on displacement of the presser roll for freeing said paper.

2. A machine of the class described, comprising a frame, a presser roller journaled in 30 the forward end of the frame, and held displaceable, a paper supporting roll adapted to feed paper to the presser roller, a paste tank fixed in the frame and adapted to supply 35 paste to one side of the paper, means normally engaging the paper to hold the same against feeding movement and automatically shifted on displacement of the presser roll for freeing said paper, and 40 means for directing the paper to the paste applying point of the tank.

3. A machine of the class described, comprising a frame, a presser roller journaled in 45 the forward end of the frame, and held displaceable, a paper supporting roll adapted to feed paper to the presser roller, a paste tank fixed in the frame and adapted to supply 50 paste to one side of the paper, means normally engaging the paper to hold the same against feeding movement and automatically shifted on displacement of the 55 presser roll for feeding said paper, means for directing the paper to the paste applying point of the tank, and friction rollers journaled at the rear end of the frame.

4. A machine of the class described, comprising a frame, a presser roller journaled in 60 the forward end of the frame, and held displaceable, a paper supporting roll adapted to feed paper to the presser roller, a paste tank fixed in the frame and adapted to supply 65 paste to one side of the paper, means normally engaging the paper to hold the same against feeding movement and automatically shifted on displacement of the 70

presser roll for freeing said paper, means for directing the paper to the paste applying point of the tank, friction rollers journaled at the rear end of the frame, and means for tensioning the presser roller when retracted.

5. A machine of the class described, comprising a frame, a presser roller journaled in the forward end of the frame, and held displaceable, a paper supporting roll adapted to feed paper to the presser roller, a paste tank fixed in the frame and adapted to supply paste to one side of the paper, means normally engaging the paper to hold the same against feeding movement and automatically shifted on displacement of the presser roll for freeing said paper, means for directing the paper to the paste applying point of the tank, friction rollers journaled at the rear end of the frame, means for tensioning the presser roller when retracted, 75 and a cutter mounted at the forward end of the frame and movable into operative position for severing the paper.

6. A machine of the class described, comprising a frame, a presser roller journaled in the forward end of the frame, and held displaceable, a paper supporting roll adapted to feed paper to the presser roller, a paste tank fixed in the frame and adapted to supply 80 paste to one side of the paper, means normally engaging the paper to hold the same against feeding movement and automatically shifted on displacement of the presser roll for freeing said paper, means for directing the paper to the paste applying point of the tank, friction rollers journaled at the rear end of the frame, means for tensioning the presser roller when retracted, 85 and a cutter mounted at the forward end of the frame and movable into operative position for severing the paper.

7. A machine of the class described, comprising a frame, a presser roller journaled in the forward end of the frame, and held displaceable, a paper supporting roll adapted to feed paper to the presser roller, a paste tank fixed in the frame and adapted to supply 90 paste to one side of the paper, means normally engaging the paper to hold the same against feeding movement and automatically shifted on displacement of the presser roll for freeing said paper, means for directing the paper to the paste applying point of the tank, friction rollers journaled at the rear end of the frame, means for tensioning the presser roller when retracted, 95 and a cutter mounted at the forward end of the frame and movable into operative position for severing the paper, and means for manually moving the cutter.

8. A machine of the class described, comprising a frame, a presser roller journaled 100

in the forward end of the frame, and held displaceable, a paper supporting roll adapted to feed paper to the presser roller, a paste tank fixed in the frame and adapted to supply paste to one side of the paper, means normally engaging the paper to hold the same against feeding movement and automatically shifted on displacement of the presser roll for freeing said paper, means for directing the paper to the paste applying point of the tank, friction rollers journaled at the rear end of the frame, means for tensioning the presser roller when re-

tracted, a cutter mounted at the forward end of the frame and movable into operative position for severing the paper, means for manually moving the cutter, means for normally holding the cutter retracted, and a handle detachably connected to the frame. 15

In testimony whereof I affix my signature 20 in presence of two witnesses.
